SYSTEM OF MOTOR CONTROL

Hermon L. Van Valkenburg, Wauwatosa, Wis.,
assignor to Square D Company, Detroit, Mich.

Application July 9, 1932, Serial No. 621,694

8 Claims. (Cl. 175—294)

This invention relates to a system of motor control.

In the operation of power systems it frequently happens that the service may be interrupted for a very short interval, which, with the ordinary system of motor control in common use, permits the controllers or contactors to open the motor circuit and thus stop the motor. This type of motor control is secured by momentary contact 5 push buttons giving what is commonly known as low voltage protection.

However, these systems are not wholly satisfactory for two primary reasons.

The first defect is due to the fact that although 15 these interruptions may be very short, nevertheless the motor circuits remain open in certain types of systems.

The second defect is due to the fact that although some systems may employ a delay device, that nevertheless, when a control station is provided at a remote point, a delay mechanism must be provided for this control station, and it is obvious, therefore, that when it is desired to have a plurality of control stations, that the 20 equipment for each station must be duplicated not only with respect to the push buttons but also with respect to the delay devices, and in addition a relatively large number of wires must be run from each control station to the main contactor, thus greatly increasing the expense 25 and complication of the system.

This invention is designed to overcome the above noted defects, and objects of this invention are to provide a novel motor control system 30 in which the contactor drops open when a momentary overload occurs, but nevertheless a time limit relay or delay device is provided and associated with the contactor so that the contactor or controller again closes the motor circuit as soon as the voltage returns to the line, while if the interruption is of longer duration, the contactor or controller remains open, and to so associate this controller with the individual control stations that each individual control station may be made with the utmost simplicity and the 35 connections from each control station to the main controller or contactor requires a minimum number of wires, each control station cooperating with the time limit device of the main contactor without requiring a duplication of the construction 40 for each control station.

Further objects are to provide a system of motor control in which any number of control stations may be employed with the utmost ease 45 and with a very simple form of wiring, and in

which each control station is itself of simple construction involving a small number of elements.

A further object of this invention is to provide a motor control system in which the time element at the contactor has a different period from the time element of each control station, so that this difference in time is utilized to secure the individual control from each control station, and in addition to secure the closing of the contactor, 10 after momentary interruptions of the service.

The invention permits the momentary depression of any stop switch or push button at any control station with the assurance that the relative timing of the delay device at each control 15 station and of the delay device or time element at the contactor is such that the contactor will open, irrespective of the length of time any of the stop buttons may be held depressed.

Embodiments of the invention are shown in the 20 accompanying drawing, in which:

Figure 1 is a diagrammatic view showing one form of the invention.

Figure 2 is a similar diagrammatic view showing a further form of the invention.

Figure 3 is a fragmentary view showing one form of dashpot or delay device.

Referring to Figure 1, it will be seen that the supply lines or mains are indicated by the reference characters 1, 2 and 3, and that connection 30 from these mains to the motor 4 is controlled by means of the contactor indicated generally by the reference character 5. This contactor is biased towards open position either by gravity or by means of the spring, the conventional illustration being employed. The contactor is closed by means of a holding coil or magnet 6, one end of which is connected to the main 3 and the other end connected to the conductor 7.

The contactor or main controller is also provided with a time limit relay which is depressed or closed by any suitable means, as for instance an arm 8 operating simultaneously with the controller and depressing the small contactor 9 so as to bridge the contacts 10 and 11. The contactor 9 may be operated in any suitable manner and is conventionally shown as operated by means of a rod 13. It is normally spring urged towards open position, but this opening is resisted by means of a timing device or delay device, such as the dashpot 14, within which a piston 15 works. Any other delay device could be used. A detail of one form of delay device or dashpot is shown in Figure 3, from which it will be seen that the piston 15 is provided with a small bleed 55

16 and with an upwardly opening check valve 17. This construction permits the quick downward motion of the piston due to the fact that the check valve opens but allows the piston to 5 slowly move upwardly. If desired, the cylinder 14 may be filled with oil. It is, however, to be distinctly understood that other types of delay devices could be used without departing from the spirit of the invention.

10 The control stations are duplicates and each may consist of a box or casing within which start and stop buttons or other types of stop and start switches are positioned. Two control stations are shown and indicated by the reference 15 characters 18 and 19, but it is to be understood that any number of control stations located at remote points from the contactor may be employed. Obviously if desired, one control station could be built in with the contactor.

20 Each control station comprises a starting button 20 provided with a contactor 21 biased towards open position and adapted to close the contacts 22 and 23. The contact 22 is connected in each case to one of the mains, for instance the 25 main 1 by means of the conductor 24.

Each control station is also provided with a stop button 25 provided with a contactor 26 biased towards closed position and normally bridging or closing the contacts 27 and 28. This 30 stop button is provided with a dashpot 29 or other time element or delay device which has a longer closing interval than the time element or delay device of the contactor.

35 A similar numbering has been employed for the contacts of the control station 19, and it is to be noted that the contacts 22 and 23 of the starting buttons are connected in parallel, whereas the stop buttons are connected in series. Each stop button is, as stated, connected in series with 40 every other stop button and is connected with the holding coil or closing coil 6 of the main contactor so that if any one of the stop buttons is open the circuit of the holding coil 6 is opened and the contactor drops open.

45 At this point it is to be noted particularly that although the time element of the contactor holds its portion of the circuit of the holding coil 6 closed, nevertheless this portion of the circuit is open prior to the closing of the stop button 50 switch due to the fact that the closing of each stop button switch at each control station requires a longer interval than that required for the opening of the time relay or time element at the main contactor.

55 On the other hand if any of the start buttons of the control stations are depressed even momentarily, the main contactor closes and instantly closes the circuit of its time element device or time relay due to the fact that the closing motion of the time relay of the main controller is substantially instantaneous, but that its opening motion is delayed the requisite length of time, as heretofore described.

65 It will be seen that a momentary interruption of service or a momentary low voltage would sufficiently deenergize the holding coil 6 as to allow the main contactor to drop open. However, if this interruption lasted only a very brief predetermined period, the time element or time relay 70 of the main contactor would not open, so that if the voltage was again restored, the contactor would again close the motor circuit. However, if the delay was greater than a predetermined value, the main contactor would remain open.

75 On the other hand, if any stop button was mo-

mentarily depressed at any control station, the contactor would instantly respond to open the motor circuit and the stop button of the particular control station would not close until after the time relay of the contactor had opened. 5

It is also to be noted that the momentary closing of any starting button would instantly close the contactor.

It is to be noted particularly that a single time relay is employed and is associated with 10 the main contactor and does not have to be duplicated for each control station so that each control station may be of very simple construction and also the wiring for each additional control station that it may be desired to add is of 15 the utmost simplicity.

The invention may take other forms, for example as shown in Figure 2. The time relay of the main controller 30 may be electrically operated 20 as distinguished from mechanically operated.

In this form of the invention the main contactor 30 is provided with an auxiliary contactor 31 adapted to bridge or close the contacts 32 and 33. These contacts 32 and 33 are connected in parallel to the contacts 34 and 35 of the electrically operated time limit relay associated with the controller, although not mechanically operated thereby. This electrically operated limit relay is provided with a magnet 36 which moves its contactor 37 upwardly to close the contacts 34 30 and 35 with a relatively quick motion. However, the downward or opening motion of the contactor is delayed by means of the dashpot or other delay device 38, the timing being similar to that previously described for the time limit 35 relay associated with the controller of the first form of the invention, the valve, however, being reversed.

The holding coil or holding magnet 39 of the main contactor is connected in parallel with the 40 coil 36 of the time limit relay. These magnets are connected through each stop button or stop switch indicated generally at 49 of each control station 41 and 42, and connected through the contacts 33 and 32 to the supply mains. 45

Inasmuch as the contacts 32 and 33 are in parallel with the contacts 34 and 35, it is obvious that the opening of the auxiliary contactor of the main contactor 30 will not open the circuit of the holding magnet 39, provided the time limit 50 relay is in closed position, and consequently if the voltage is again restored within a predetermined time, the contactor will again close the motor circuit, as in the form previously described.

Each starting button indicated generally at 43 55 at each of the substations is adapted to momentarily close the circuit of the closing magnet 39 and the magnet 36 of the time relay, as each starting button is connected in parallel and establishes connection from one side of each of the 60 magnets 36 and 39 to the main 1, the other side of each of the magnets 36 and 39 being connected to the main 3.

Each of the stop buttons is provided with a time limit device, such as the dashpot indicated 65 by the reference character 44, which permits a quick opening motion but a delayed closing motion, the timing of the closing being greater than the timing of the opening of the element 38 of the time limit relay.

In this form of the invention it is preferable to build the time limit relay in with the main contactor, as previously described, although obviously it could be located at a separate point if for any cause such construction was desired. 70 75

It is also apparent that the same simplicity obtains with this form of the invention as that previously described, in that any number of control stations may be added without duplicating the time relay and without complicating the wiring.

It will be seen that a novel form of motor control system has been provided in which any number of control stations may be employed with a very simple form of wiring and without undue complication in the wiring system, irrespective of the number of control stations employed.

It will be seen further that although low voltage protection is secured through a time relay or time element adapted to restore service for momentary interruptions which exist for a limited, predetermined time, that nevertheless it is not necessary to duplicate this time relay as additional control stations are provided, as each control station cooperates with the single time limit relay employed with the main contactor or main controller.

Although this invention has been described in considerable detail it is to be understood that such description is intended as illustrative rather than limiting, as the invention may be variously embodied and is to be interpreted as claimed.

I claim:

1. In a motor control system, a main contactor, a delayed action time relay, a holding circuit for said main contactor controlled by said time relay, said time relay being biased towards contactor-open position, a plurality of control stations, each control station having a starting switch and a stop switch, each stop switch cooperating with said time relay for controlling the holding circuit and means for each stop switch for positively closing said stop switch at a rate less than the rate of action of said time relay.

2. In a motor control system, a main contactor, a delayed action time relay, a holding circuit for said main contactor controlled by said time relay, said time relay being biased towards contactor-open position, a plurality of control stations, each control station having a starting switch and a stop switch, each stop switch cooperating with said time relay for controlling the holding circuit, and means for each stop switch for positively closing said stop switch at a rate less than the rate of action of said time relay, the opening of any stop switch or of said time relay serving to open said holding circuit, said starting switches operating in parallel to said time relay.

3. In a motor control system, a main contactor, holding means for said main contactor responsive to circuit conditions, said holding means including a delayed action device, and a delayed action stop switch cooperating with said holding means, said stop switch except for the delayed action being free to move towards closed position, a spring urging said stop switch towards closed position, said stop switch having a greater delay

in returning to its closed position than said delayed action device has in moving to its open position.

4. In a motor control system, a main contactor, holding means responsive to circuit conditions for normally holding said main contactor closed, said holding means including a delayed action device biased toward open position, and a push button stop switch for opening said main contactor, said push button stop switch being permanently biased towards closed position and having delayed action means retarding its return to closed position for an interval of time greater than that of said delayed action device has in moving to its open position.

5. In a motor control system, a main contactor, a delayed action time relay biased toward open position, a holding circuit for said main contactor controlled by said delay action time relay, a stop switch in said holding circuit permanently biased towards closed position, and delay means for delaying the closing motion of said stop switch for a longer interval than that of said delayed action time relay in moving to open position.

6. In a motor control system, a main contactor, a delayed action time relay biased towards open position, a holding circuit for said main contactor controlled by said delay action time relay, a starting switch for initially closing said holding circuit, a stop switch in said holding circuit permanently biased towards closed position, and delay means for delaying the closing motion of said stop switch for a longer interval than that of said delayed action time relay in moving to its open position.

7. In a motor control system, a main contactor, a delayed action time relay biased towards open position, a holding circuit for said main contactor controlled by said time relay, a plurality of control stations, each control station having a starting switch and a stop switch, each stop switch cooperating with said time relay for controlling the holding circuit, the opening of any stop switch serving to open said holding circuit, a spring biasing each stop switch towards closed position, each stop switch having a delayed closing action slower than the delay of the time relay in moving towards open position.

8. In a motor control system: a main contactor; a delayed action time relay biased towards open position; a holding circuit for said main contactor controlled by said delayed action time relay; and a plurality of control stations, each control station having a push button starting switch biased towards open position for initially closing said holding circuit, and a push button stop switch permanently biased towards closed position and having delay means delaying its closing motion for a greater interval of time than that of said delayed action time relay in moving towards open position, each of said stop switches being connected in series in said holding circuit.

HERMON L. VAN VALKENBURG.
